UNITED STATES PATENT OFFICE.

JOHN L. NILSON AND JOHN F. PRINCE, OF CHICAGO, ILLINOIS.

RADIO CONDENSER ADJUSTMENT.

Application filed October 1, 1924. Serial No. 740,927.

Our invention relates to radio receiving instruments, and has particular reference to the condensers thereof. The object of the present improvement is the provision, 5 in a compact, or space-saving, arrangement for changing the relative capacity of a plurality of condensers in a set by making a part of the stators, as well as the rotors, adjustably movable, and our invention consists 10 in the novel construction, combination and arrangement of parts, hereinafter described in detail, illustrated in the accompanying drawing and more particularly pointed out in the appended claims.

15 In the accompanying drawing—

Figure 1 is a plan view of a set of three condensers together with a broken away portion of the base-board and dial panel, the blades of the condensers being shown 20 diagrammatically.

Figure 2 is an enlarged side view in elevation of one of the identical condensers, taken substantially on the line 2—2 of Figure 1, with the upper portion of the panel 25 broken away.

Figure 3 is an enlarged section taken substantially on the line 3—3 of Figure 2, showing the eccentric or cam by means of which the two end stators of the set are adjusted 30 on the axis of the condenser shaft.

In the several views 2 represents the base-board, or part over which the condensers are mounted, and 3 represents the usual panel on the face of which is or are placed 35 the dial or dials 15. The condensers, including all the parts of each, are indicated as 4, 5 and 6, respectively, the middle one—5—having its stator portion fixed in the usual manner, while the two end condensers 40 have their stators as well as their rotors mounted for rotary adjusting movement. Each of these condensers is represented in Figures 1, 2 and 3 as having triangular frame-ends 7 and 8, between which are the 45 rotor plates 9 and stator plates 10 shown diagrammatically in Figure 1. The respective rotors are secured to, or keyed to, the usual rotary shaft or spindle—11—, which 50 parallels the panel, while the stator blades are secured to suitable cross-pieces 12 and 13 (Figure 1) between the sides or ends 7 and 8. In Figure 1 the shaft 11, to which all the rotors are keyed, is rotated by a finger knob 14 on a dial 15. The knob 14 is keyed to a shaft 16 on the inner end of 55 which is keyed a bevel gear 18 adjacent to a bearing post 17 for the shaft 16. The gear 18 meshes with a similar gear 19 that is keyed to the shaft 11, the ends of which are mounted on bearings 20 and 21. In 60 order to provide for the rotary movement of the stators indicated by dotted lines in Figure 2, the condensers are elevated by the shaft 11, the stator of the condenser 5, or the ends 7 and 8 thereof, being provided 65 with a separate base-board 22 the position of which relative to the middle condenser being indicated by dotted lines in Figure 2. The stator, or condenser frame, of each of the condensers 4 and 6 is rotatably supported by the shaft 11, and is adjustably held stationary by the mechanism shown on an enlarged scale in Figures 2 and 3, as well as on a smaller scale in Figure 1. This mechanism consists of a cam or eccentric 70 23 that is eccentrically keyed to a shaft 24 mounted in the panel 3 and on a bearing-bracket 25, the bearing in the panel being represented by a bore 26. On the cam 23 is a ring or strap 27 from which depends a lug 28 through which is a bore 29 to receive a stud or bolt projecting from the outer side of the end or side frame-piece 7, which projection may be an extension of the usual frame cross-rods—30—having thereon 75 the nuts 31. To the outer end of the shaft 24 is secured a turning knob, or finger-piece 32 secured as by a pin 33. These knobs, like the knob 14, may be provided with suitable indicating dials such as 15. The 80 mechanism for rotating the latter in the usual and various ways, not forming a part of the present improvement, is not shown.

The customary adjustment of the rotors through the medium of the knob 14 to vary 85 the capacity of the condensers, may, by the rotary adjustment of one or more of the stators in the manner herein shown, be thus minutely and accurately corrected, either plus or minus by manipulation of one or more knobs 32 which control the stator positions.

The common "tuned radio frequency" receiver, whether under conditions wherein 90 it becomes a neutrodyne, or a simple self-balancing circuit, makes use of three "tuned circuits", each consisting of coil or inductance and condenser or capacity. The 95 condenser is the only variable element. The three tuned circuits require three variable 100 condensers with three dials, according to 110 the general practice. The frequency to

which each tuned circuit responds is, disregarding constants, directly proportional to the product of inductance and capacity, whose values are very small while their frequencies are very large or high. Hence an infinitesimal change in either inductance or capacity, or in both, will make a very large change in the frequency. Changes which are extremely minute in themselves will be reflected in great frequency changes, and these minute changes may be caused by the deposit of dust in condensers, or in changes of temperature or humidity in either of the three circuits independently of the others.

15 In the present improvement such changes may be compensated for by a very slight angular movement, or rotation, of the usually fixed portion of the condenser, or stator.

20 In the early stages of this art the problem of providing mechanisms which would operate within a minimum of space, was not present to any appreciable extent. But as the art progresses the avoidance of the large spread of parts and the simplification of mechanisms and arrangements thereof is of growing importance. In the present improvement by supporting the shaft 11 on the two bearing standards 20 and 21 at the

outer ends of the battery of condensers we have adapted our invention to existing and approved form of condensers and the cam arrangement for moving individual stators, unlike the more or less complex and spread out mechanisms for the same purpose (which are now wholly unavailable for commercial purposes) invented in the early stages of the art, call for no space increases in existing receiving sets.

We claim as our invention.

1. In combination, a panel, a plurality of condensers, a single shaft for same paralleling said panel, turning knobs with short shafts thereon which have their inner ends adjacent to rotatably mounted stator frames, the stator frames, and stator-rotating means between said inner ends and stators.

2. In combination, a plurality of condensers on a single shaft, rotatably mounted condenser stators, a turning knob with a short shaft thereon for rotating individual stators separately, and cam-members on said short shaft and individual stator, respectively, for adjustably rotating the individual stator.

In testimony whereof we have hereunto signed our names.

JOHN L. NILSON.
JOHN F. PRINCE.
